UNITED STATES PATENT OFFICE.

HAROLD J. DINGER, OF WHEELING, WEST VIRGINIA, ASSIGNOR OF ONE-HALF TO C. H. ROLLASON, OF WHEELING, WEST VIRGINIA.

SHOCK-ABSORBING SPRING.

Application filed March 15, 1924. Serial No. 699,524.

This invention relates broadly to vehicle springs, and more specifically to a combined cushioning spring and recoil check for vehicles.

5 The primary object of the invention is to provide a simple and comparatively inexpensive device whereby is effected in large measure a reduction in the vibratory movements of road vehicles to which it is applied.

10 A further object is to provide a device which effectively prevents not only the transmission of primary road shocks to the frame and body of the vehicle, but also such secondary shocks as ordinarily result from rebounds or recoil forces.

15 In describing the invention in detail, reference is herein had to the accompanying drawings, in which—

Figure 1 is a central longitudinal section of the invention, illustrating its application;

20 Figure 2 is an enlarged detail section of an end portion of the spring enclosing cylinder;

25 Figure 3 is an end view of the same;

Figure 4 is an enlarged side elevation of the cylinder support;

Figure 5 is an end elevation of the same;

30 Figure 6 is an enlarged side elevation of a cylinder-carried bracket;

Figures 7 and 8 are, respectively, an outer end elevation and a top plan view of the same;

35 Figures 9 and 10 are views similar to Figs. 4 and 5, respectively, illustrating a form of support employed when the invention is modified to embody two parallel cylinders;

40 Figures 11, 12 and 13 are views similar to Figs. 6, 7 and 8, respectively, showing the form of cylinder-carried bracket employed in connection with two cylinders;

45 Figures 14 and 15 are, respectively, a side elevation and an outer end elevation of the bell-crank employed in connection with the two-cylinder type of the invention;

50 Figure 16 is a view similar to Fig. 1, illustrating a modified form of the invention in which a fluid is employed for cushioning rebound forces;

55 Figure 17 is an enlarged detail section of an end portion of the cylinder shown in Fig. 16; and—

Figure 18 is a section on line 18—18, Fig. 17.

55 Referring particularly to Figs. 1 to 8 of

the drawings, the reference numeral 1 indicates an axle of a vehicle, and 2 a side member of the frame which is supported over said axle. Rigidly attached to said axle, as by means of the clamp-like support shown 60 in Figs. 1, 4 and 5, is a hollow tubular member or cylinder 3, the same being carried at right angles to said axle and having its opposite ends extending forwardly and rearwardly from said axle throughout an appropriate distance. Said support, as herein shown, comprises a pair of clamp members 4 and 5 which complementally embrace the axle 1, and a clamp member 6 which complements the member 5 in embracing said 70 cylinder 3. Bolts 7 of U-shape directed through the members 4, 5 and 6 serve to secure said members in a position tightly clamping the cylinder to the axle.

Rigidly mounted upon the cylinder adjacent to each of its opposite ends is the sleeve portion of an upstanding bracket 8 which has an arm 8^a. The arms 8^a of the brackets mounted upon the front and rear ends of said cylinder extend, respectively, 75 forwardly and rearwardly beyond said ends and constitute supports upon which are pivotally mounted the angular portions of bell-crank levers 9. The foremost of said levers has one arm thereof extending forwardly and pivotally attached at its ends to a bracket 10 which is fixed to the side frame 2 of the vehicle. The other arm of said foremost lever 9 has a downward and forward inclination and has pivotally attached thereto an 80 end of a link 11 which has its opposite end pivotally attached to the projecting end of a plunger rod 12. Said rod carries upon its inner end a head or plunger 13 and is longitudinally movable within said cylinder. A 85 similar rod 14 and plunger 15 is operable within the opposite end of the cylinder, and the projecting end of said rod 14 has connection through a pivoted link 16 with the downwardly and rearwardly inclined arm of the rearmost of the bell-crank levers 9. The other arm of the last mentioned lever is pivotally connected to the adjacent end of the frame or to a pivoted link 17 having 90 connection with said frame, as shown. 100

Interposed between the two plungers is a spiral compression spring 18 which normally maintains said plungers in the widely separated relative positions shown in Fig. 1. Said spring serves as a buffer for yieldingly 110

resisting and absorbing primary road shocks, which shocks induce relative approach of the axle 1 and frame 2 and which act through the link and lever mechanism hereinbefore described to thrust the plunger inward with respect to the cylinder.

Each of the plunger rods is movable through a suitable guide, as the plug 19, which is removably mounted in each end 10 of the cylinder 3. Interposed between each of said plugs and the adjacent plunger and disposed in encircling relation to the plunger rod is a compression spring 20. Said springs 20 are designed to yieldingly retard the return, or separating, movements of the plungers induced by the rebound or recoil force exerted by the buffer spring 18 following the abnormal compression to which the latter is subjected, as aforesaid, 20 and thus to absorb a very large proportion of the secondary shocks induced by such rebounds.

In the modified form of the invention illustrated in Figs. 9 to 15, inclusive, a pair 25 of parallel cylinders 3' are substituted for the single cylinder 3, and the forms of the parts associated therewith are accordingly changed, the clamp-like cylinder supports being shaped for the reception of two cylinders, as shown in Figs. 9 and 10, brackets 8' adapted for mounting upon two cylinders being provided, as shown in Figs. 12 and 13, and bell-crank levers 9' for attachment to said levers being employed, as shown 30 in Figs. 14 and 15.

In the modification illustrated in Figs. 16 to 18, inclusive, the springs 20 are omitted and the cylinder 3 is shown as filled with a suitable fluid, as oil. Passages or ports, as 40 21, provided in the plungers 13' and 15' permit of the passage of the fluid from one side of the plunger to the other. Said fluid acts in an obvious manner to retard the movements of said plungers and thus to

cushion shocks and reduce vibration between 45 the vehicle axle and frame.

What is claimed is—

1. The combination with a vehicle axle and frame, of a cylinder disposed transversely with respect to and supported by said axle, 50 plungers movable within the opposite end portions of said cylinder, rods carrying said plungers having their ends projecting outward from the opposite ends of said cylinder, guides for said rod carried by the opposite ends of said cylinder, a buffer spring interposed between said plungers, means 55 interposed between said plungers and the adjacent guides for retarding separating movements of said plungers, supporting brackets carried by the opposite end portions of said cylinder, and a bell-crank lever pivoted to each of said brackets, one arm of said lever having pivoted connection with said rod and the other arm thereof having pivotal connection 60 with the vehicle frame.

2. The combination with a vehicle axle and frame, of a cylinder disposed transversely with respect to and supported by said axle, plungers movable within the opposite 70 end portions of said cylinder, rods carrying said plungers having their ends projecting outward from the opposite ends of said cylinder, guides for said rod carried by the opposite ends of said cylinder, movement-retarding cushioning means interposed 75 between said plungers, means within the end portions of said cylinder for yieldingly retarding separating movements of said plungers, a supporting bracket carried on each 80 end of said cylinder, and a bell-crank lever pivotally carried by said bracket, said lever having one arm thereof pivotally connected to said frame and its other arm pivotally connected to the adjacent plunger rod.

In testimony whereof, I affix my signature.

HAROLD J. DINGER.
